UNITED STATES PATENT OFFICE.

DANIEL R. SHERWOOD, OF PLAINFIELD, NEW JERSEY, ASSIGNEE TO HENRY B. NEWHALL, OF PLAINFIELD, NEW JERSEY.

EXPANSION BOLT.

1,417,209.

Specification of Letters Patent. Patented May 23, 1922.

Application filed March 9, 1921. Serial No. 450,920.

To all whom it may concern:

Be it known that I, DANIEL R. SHERWOOD, a citizen of the United States, residing at Plainfield, in the county of Union and State 5 of New Jersey, have made certain new and useful Improvements in Expansion Bolts, of which the following is a specification taken in connection with the accompanying drawings.

10 My invention relates to expansion bolts and more particularly to the combination of an expansion bolt and a removable escutcheon plate; and also to the escutcheon plate and the expansion bolt as separate articles 15 of manufacture.

My invention further relates to such a combined expansion bolt and escutcheon plate having a maximum grip or hold in the wall or ceiling for a given size of expansion.

20 My invention further relates to an expansion the outer end of which lies substantially flush with the surface of the wall or ceiling, and a removable escutcheon plate having an unbroken inner surface to lie flat 25 against a wall, or other suitable support, and means to hold the expansion and the escutcheon plate together.

30 My invention further relates to certain combinations, details of construction, and articles of manufacture, which will be more fully hereinafter described and pointed out in the claims.

35 In the accompanying drawings the same reference numerals refer to similar parts in the several figures.

Fig. 1 is a vertical section through a wall, ceiling or other suitable support showing one form of my expansion bolt and escutcheon plate;

40 Fig. 2 is a fragmentary plan view;

Fig. 3 is a vertical section on the line 3—3 of Fig. 1, looking in the direction of the arrows;

45 Fig. 4 is a rear elevation of the form of escutcheon plate shown in Fig. 1;

Fig. 5 is a detail view showing the manner of assembling the expansion and the escutcheon plate;

50 Fig. 6 is a vertical section showing the two members assembled;

Fig. 7 is a side elevation of a modified form of my invention;

Fig. 8 is a vertical section on the line 8—8 of Fig. 7, looking in the direction of the 55 arrows;

Fig. 9 is a rear elevation of the inner surface of the removable escutcheon plate shown in Fig. 7;

Fig. 10 is a detail view showing the manner of assembling the escutcheon plate of 60 Fig. 9 and the expansion shown in Fig. 7;

Fig. 11 is a detail view showing the parts assembled;

Fig. 12 is a vertical section, partly in side elevation, of a modified form of my invention; 65

Fig. 13 is a fragmentary detail plan view;

Fig. 14 is a vertical section substantially on the line 14—14 of Fig. 12;

Fig. 15 is a rear elevation of the escutcheon plate shown in Fig. 12; 70

Fig. 16 is a detail view showing the manner of assembling the expansion and the escutcheon plate shown in Fig. 12;

Fig. 17 is a detail view showing the expansion and the escutcheon plate completely 75 assembled.

It has been proposed to secure a removable cap or plate to an expansion bolt, the head of which is permitted to extend out of 80 the opening in the wall or ceiling a sufficient distance to become imbedded or seated in, and enclosed by, a hollow removable plate. Among other disadvantages this is objectionable in that the expansion is not inserted 85 its full length in the hole and therefore its effective expansion surface is materially lessened. To carry a given load a larger expansion is required than one in which the expansion bolt proper is inserted for its 90 whole length within the hole. It is further objectionable in that it brings a powerful expansion force near the outer surface of the wall or ceiling which is apt to cause the surface or wall to crack around the hole, requiring a larger plate than if the expansion 95 force was thrown well back into the hole and removed from the surface of the wall or ceiling.

By my invention I permit the full length 100 of the expansion to be inserted in the wall, ceiling or other suitable support, and therefore insure that the powerful expansion is exerted well back from the surface of the wall or ceiling, thereby insuring both a 105 stronger expansion for a given size of expansion bolt, and also protecting the surface of the wall or ceiling from cracking or crumbling as the expansion force is applied to the expansion bolt. This permits me to 110

use an escutcheon plate of the minimum size and therefore one requiring less metal and cheaper to manufacture. Being relatively small it is less obtrusive and enhances the 5 appearance of the job.

In the drawings I have shown different embodiments of my invention used in connection with what is known in the trade as a machine expansion. It is to be distinctly 10 understood, however, that any form of expansion may be used whether operated by a machine bolt, a lag screw or any other suitable means.

I have shown one form of my invention 15 in Figs. 1 to 6 inclusive. In these figures 1 is a wall or ceiling formed of any suitable material usually of concrete. In this wall the hole 2 is formed in any suitable manner as by drilling to receive the expansion 3. 20 This expansion may be of any suitable form. For purposes of illustration I have shown it formed of two members 4 and 5 having parallel ribs 6—6; the two members are expanded by a wedge 7 carried by a nut 25 8 operated by the machine bolt 9. As this machine bolt 9 is screwed within the nut 8 it causes the nut to move between the members 4 and 5 and expand them with tremendous force, the expansion being somewhat exaggerated in Fig. 1 for purposes of illustration.

My invention is adapted for universal adaptation and is particularly useful for hanging pipes from ceilings or walls, as for 30 example in automatic fire sprinkling installations. It is desirable to make as neat a job as possible and give a finished appearance to the entire installation. By my invention the expansion 3, with the members 4 and 5 contacting with each other as shown 35 in Fig. 7, is inserted in the hole 2, leaving only the neck 10 of the expansion out of the hole 2. Then, or prior thereto, if desired, the removable escutcheon plate 11 is 40 secured to the expansion 3 in any suitable manner. I have shown in Figs. 1 to 6 the escutcheon plate 11 provided with locking fingers 12 and 13.

To assemble the parts, prior to the insertion of the machine bolt 9, the locking finger 12 is inserted in the pocket or groove 14 in the member 5. The other locking finger 13 is then brought on one side or the other of the longitudinal axis extending 45 through the expansion 3. The escutcheon plate 11 is then swung down in the direction of the arrow, as shown in Fig. 5, until the finger 13 engages in the groove 15. This brings the two locking fingers 12 and 13 in 50 the same vertical plane, Figs. 1 and 6, in which position the escutcheon plate is secured to the expansion. To bring the inner surface 16 of the escutcheon plate 11 flush against the outer surface 17 of the ceiling or wall 1, and also to insure that the ex-

pansion 3 is inserted its maximum length in the hole 2 so as to obtain the maximum hold or grip, the escutcheon plate is given a soft blow with a hammer or any suitable tool so as to cause the fingers 12 and 13 to 50 become embedded in the concrete or other suitable matter of the wall or ceiling as shown in Fig. 1. The bolt 9 is then inserted through the hole 18 in the escutcheon plate 11 and cooperates with the nut 8 which 55 moves between the members 4 and 5 and expands them as the machine bolt is turned. This expansion is shown somewhat exaggerated in Fig. 1. It will be noted that the expansion force takes place well back of the 60 surface 17 of the wall or ceiling and that the fingers 12 and 13 also tend to prevent any expansion of the expansible members 4 and 5, which would be sufficient to crumble or crack the surface of the wall or 65 ceiling 17 adjacent to the hole or opening 2. A pipe or any other suitable object may be suspended from the bolt 9.

When the bolt 9 is inserted through the escutcheon plate 11 and engages with the 70 nut 8 it is impossible to remove the escutcheon plate without first removing the bolt. This permits the expansion, the escutcheon plate and the bolt to be assembled and shipped as one unitary article. Of course, 75 it is to be understood that the expansion and the escutcheon plate may be sold and shipped as separate articles of manufacture, if so desired.

In Figs. 7 to 11 I have shown another 80 modification of my invention in which the expansion 19, Fig. 7, has a neck 21 provided with cam grooves 22, 22, Fig. 8. In assembling the escutcheon plate 23 and the expansion 19 they are brought into the position of 85 Fig. 10 where the fingers 12 and 13 are about to be received in the deepest portions of the cam grooves 22, 22. The escutcheon plate 23 is then moved across the end of the expansion until the expansion 19 contacts with the 90 stop 24 on the escutcheon plate. The escutcheon plate is then rotated in either direction with relation to the expansion 19 so as to bring the locking fingers 12 and 13 up on the cams 22, 22, when the escutcheon plate is 95 secured to the expansion and ready to be inserted in the wall or other suitable support in the same manner, as described in connection with the other construction.

In Figs. 12 to 17 I have shown another 100 modification of my invention in which the expansion 24 at its outer end has a neck 25 provided with a groove 26, the groove being provided with a hole 27. The removable escutcheon plate 28 is provided with two relatively long locking fingers 29 and 30. In attaching the escutcheon plate 28 it is merely necessary to locate one of the fingers, as for example 29 in the hole 27, and then rock or pivot the removable escutcheon plate 28 105 110 115 120 125 130

upon that finger 29 in the direction, for example, shown by the arrow in Fig. 16, until these two fingers 29 and 30 are brought in the same vertical plane as shown in Fig. 17.

5 The machine bolt 9 is then inserted.

It will, therefore, be clear that in all forms of my invention the maximum grip will be insured for a given size expansion, that this expansion will be located entirely within the 10 hole and removed from the face of the wall, ceiling or other suitable support. The expansion is inserted simply by placing it in the hole, the final adjustment being made by means of a soft blow from a hammer or mallet or any other suitable tool. The escutcheon plate being relatively small it will take less metal and will be comparatively inexpensive to manufacture, besides it will be inconspicuous in use.

20 Having thus described this invention in connection with illustrative embodiments thereof, to the details of which I do not desire to be limited, what is claimed as new and what is desired to secure by Letters Patent is set forth in the appended claims.

What I claim is:—

1. The combination of an expansion bolt,

a detachable escutcheon plate, and means to hold the end of the expansion bolt against the inner surface of the escutcheon plate and 30 in substantially the same vertical plane as the inner surface of said plate.

2. The combination of an expansion bolt, a detachable escutcheon plate, and fingers to hold the end of the expansion bolt against 35 the inner surface of the escutcheon plate and in substantially the same vertical plane as the inner surface of said plate.

3. An expansion bolt provided with a hole 40 near its outer end to receive and hold a pivoting and locking finger on a removable escutcheon plate and also provided with a groove to cooperate with another locking finger.

4. A new article of manufacture comprising an expansion bolt and a removable escutcheon plate lying snug against the end of the expansion bolt but not embracing it, and means to removably hold the escutcheon plate and expansion bolt together.

DANIEL R. SHERWOOD.
